UNITED STATES PATENT OFFICE.

REVRA DE PUY, OF WARSAW, INDIANA.

DESIGN FOR A PUMP-FRAME.

SPECIFICATION forming part of Design No. 30,578, dated April 18, 1899.

Application filed November 17, 1898. Serial No. 696,732. Term of patent 7 years.

To all whom it may concern:

Be it known that I, REVRA DE PUY, a citizen of the United States, residing at Warsaw, in the county of Kosciusko and State of Indiana, have invented and produced a new and original Design for a Pump-Frame, of which the following is a specification, reference being had to the accompanying drawing, forming part thereof.

10 The accompanying illustration is a perspective showing my new design.

As shown in the drawing, the leading or material feature of my design consists in a rectangular base 3, surmounted by two cylindrical bodies 1 and 2, one of which ranges

vertically and the other horizontally, the two cylindrical bodies being partially embedded together.

Having described my invention, what I claim as new, and desire to secure by Letters 20 Patent, is—

The design for a pump-frame, as herein shown and described.

In testimony whereof I affix my signature in presence of two witnesses.

REVRA DE PUY.
